Primary Examiner — Darcey E Gottschalk

(74) **Attorney, Agent, or Firm:** Jose Cherson Weissbrot

(57) **CLAIM**

The ornamental design for a muscle stimulator, as shown and described.

DESCRIPTION

FIG. 1 is a front perspective view of a muscle stimulator in an opened state, showing my new design;

FIG. 2 is another front perspective view in another angle thereof;

FIG. 3 is a rear perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is a front perspective view of a muscle stimulator in a closed state.

The broken lines in the figures are for the purposes of illustrating portions of the muscle stimulator, which form no part of the claimed design.

1 Claim, 10 Drawing Sheets
